DESIGN FOR A COMBINATION BABY AND GROCERY CARRIER

George Silvera, Table Grove, Ill.

Application August 10, 1945, Serial No. 121,357

Term of patent 14 years

(Cl. D14—14)

To all whom it may concern:

Be it known that I, George Silvera, a citizen of the United States, residing at Table Grove, in the county of Fulton and State of Illinois, have invented a new, original, and ornamental Design for a Combination Baby and Grocery Carrier, of which the following is a specification, reference being had to the accompanying drawing, forming part thereof.

In the drawing:

Fig. 1 is a perspective view of a combination baby and grocery carrier showing my new design

and looking principally toward the front and one side of the carrier; and

Fig. 2 is a perspective view thereof looking principally toward the rear and opposite side of the carrier.

The characteristic features of my design are shown in full lines.

I claim:

The ornamental design for a combination baby and grocery carrier, substantially as shown and described.

GEORGE SILVERA.
